(57) **CLAIM**

The ornamental design for a control unit, as shown and described.

DESCRIPTION

FIG. 1 is a top perspective view of a first configuration of a control unit showing our new design, with the control unit seated within its receptacle and with the hinged-panel in a closed position;

FIG. 2 is a top plan view thereof;

FIG. 3 is a rear elevational view thereof;

FIG. 4 is a right side elevational view thereof;

FIG. 5 is a front elevational view thereof; and

FIG. 6 is a left side elevational view thereof.

FIG. 7 is a top perspective view of a second configuration of a control unit showing our new design, with the control unit shown separately from its receptacle for clarity of detail and with the hinged-panel in a closed position;

FIG. 8 is an alternate top perspective view thereof;

FIG. 9 is a top plan view thereof;

FIG. 10 is a rear elevational view thereof;

FIG. 11 is a left side elevational view thereof;

FIG. 12 is a front elevational view thereof; and

FIG. 13 is a bottom plan view thereof.

FIG. 14 is a top perspective view of a third configuration of a control unit showing our new design, with the control unit shown separately from its receptacle for clarity of detail and with the hinged-panel in an opened position;

FIG. 15 is an alternate top perspective view thereof;

FIG. 16 is a top plan view thereof;

FIG. 17 is a rear elevational view thereof;

FIG. 18 is a left side elevational view thereof;

FIG. 19 is a front elevational view thereof; and

FIG. 20 is a bottom plan view thereof.

FIG. 21 is a top perspective view of a fourth configuration of a control unit showing our new design, with the control unit seated within its receptacle and with the hinged-panel in an opened position;

FIG. 22 is a rear elevational view thereof; and,

FIG. 23 is a front elevational view thereof.

The broken line portion of the figure drawings is included to show unclaimed subject matter only and forms no part of the claimed design.
